Primary Examiner — Rachel A. Voorhies

Assistant Examiner — Benjamin D. Wannemacher

(74) Attorney, Agent, or Firm — IPath PLC; Steven J. Miller, Esq.

(57) **CLAIM**

The ornamental design for a flooring tile connector as shown and described.

DESCRIPTION

1. Flooring tile connector

1.1 : Perspective

1.2 : Perspective

1.3 : Front

1.4 : Back

1.5 : Top

1.6 : Bottom

1.7 : Left

1.8 : Right

Nos. 1-8; A tile connector is claimed as shown in FIGs. 1-8.

1 Claim, 8 Drawing Sheets(56)
